(57) **CLAIM**

The ornamental design for a support cradle, as shown and described.

DESCRIPTION

FIG. 1 is a front perspective view of the support cradle embodying the present invention;

FIG. 2 is a front elevational view of the support cradle;

FIG. 3 is a top view of the support cradle;

FIG. 4 is a right side view of the support cradle, with the left side view being a mirror image thereof;

FIG. 5 is a bottom view of the support cradle; and,

FIG. 6 is a back elevational view of the support cradle.

The phantom lines shown in FIGS. 1–6 are shown for illustrative purposes only and form no part of the claimed design.
